UNITED STATES PATENT OFFICE.

ANTONIO ZIRION Y SARAVIA, OF MEXICO, MEXICO, AND RAMON M. RODRIGUEZ, OF NEW YORK, N. Y., ASSIGNORS TO DERMOPHILE PRODUCTS COMPANY, INC., OF NEW YORK, N. Y., A CORPORATION OF NEW YORK.

DESIGN FOR A BOX FOR TALCUM POWDERS AND THE LIKE.

Application filed June 5, 1922. Serial No. 2,527. Term of patent 14 years.

To all whom it may concern:

Be it known that we, ANTONIO ZIRION Y SARAVIA, a citizen of Guatemala, Central America, and a resident of Mexico city, Mexico, and RAMON M. RODRIGUEZ, a citizen of the United States of America, and a resident of the borough of Manhattan, city, county, and State of New York, have jointly invented a new, original, and ornamental Design for Box for Talcum Powders and the like, of which the following is a specification.

Reference is to be had to the accompanying drawing, which illustrates in elevation a box embodying the design.

The design relates to boxes intended more particularly for talcum powders and the like.

We claim:

The ornamental design for a box for talcum powders and the like as shown.

ANTONIO ZIRION Y SARAVIA,
RAMON M. RODRIGUEZ.
